(57) **CLAIM**

I claim the ornamental design for a tri-fold display blank, as shown and described.

DESCRIPTION

FIG. 1 is a front view of a tri-fold display blank in accordance with a first embodiment of the present invention.

FIG. 2 is a front view of a tri-fold display blank in accordance with a second embodiment of the present invention.

FIG. 3 is a rear view of the tri-fold display blank of FIG. 2.
FIG. 4 is a front perspective view of a tri-fold display blank shown in a partially assembled configuration formed from the blank of FIG. 1.

FIG. 5 is a front perspective view of a tri-fold display blank shown in a fully assembled state formed from the blank of FIG. 1.

FIG. 6 is a front view of the assembled tri-fold display blank of FIG. 5.

FIG. 7 is a rear view of the assembled tri-fold display blank of FIG. 5.

FIG. 8 is a top view of the assembled tri-fold display blank of FIG. 5.

FIG. 9 is a bottom view of the assembled tri-fold display blank of FIG. 5.

FIG. 10 is a left-side view of the assembled tri-fold display blank of FIG. 5; and,

FIG. 11 is a right-side view of the assembled tri-fold display blank of FIG. 5.

The broken lines formed by linear segments of equal length in FIGS. 1-3 represent pre-weakened areas in the blank. The stippling in FIG. 2 indicates an adhesive. The gray shading in FIG. 3 represents a contrasting surface appearance from what is shown on the opposite side.
